DEFLECTING COIL FOR CATHODE RAY TUBES

Ernst Ruska, Berlin-Zehlendorf, Germany, assignor to the firm Fernseh Aktiengesellschaft, Zehlendorf, near Berlin, Germany

Application September 16, 1936, Serial No. 101,173
In Germany September 30, 1935

5 Claims. (Cl. 250—156)

In cathode ray tubes such as for example oscilloscope tubes and television transmitting and receiving tubes the problem arises of deflecting the ray free from distortion in one or in a number of directions. It is especially true, when the ray is not sharply bundled together, as is the case in ordinary television receiving tubes or in tubes using a photocell mosaic, so that the ray has a large cross section, as in the Farnsworth image scanning tubes using a photocathode, that it is difficult to produce magnetic fields having an adequately homogeneous shape in the entire deflectional space. If the deflection in addition is to be effected at high frequency and of adequate sensitivity so as to permit use of fewer ampere turns, the coil system used for producing the deflecting field must have dimensions which are as small as possible. The conductors of the coil must therefore be disposed as close as possible to the space in which the ray moves, without deleteriously affecting the homogeneity of the field in this space.

It is already known to make the deflecting coils in the form of rectangular coils and so to dispose them on both sides of the tube neck of a Braun tube that together they form a rectangular frame surrounding the neck of the tube. The longitudinal conductors in that case lie in two planes on both sides of the neck of the tube. In such an arrangement, however, the field in the deflecting space is not homogeneous since the lines of force in the vicinity of the tube axis are forced together and tend to deviate outwardly in a spread-apart manner.

In accordance with the invention a homogeneous field is produced by means of coils constructed in a special manner. The coil is so formed that the longitudinal conductors which produce the deflecting field together constitute the casing of a cylinder disposed coaxial to the direction of the principal ray. The coil is so wound that on one side of an axial section taken through this cylinder the current flows only in one direction and on the other side only in the other direction. The electrical axis of the coil therefore lies in this section and is perpendicular to the axis of the cylinder or tube.

The longitudinal conductors are preferably non-uniformly distributed on the casing surface and in such a manner that the current layer projected on the axial section and passing through the electrical axis of the coil is constant. Such a distribution of the winding permits the production of a very homogeneous field inside the coil space.

In some cases it is desirable to give the deflecting field a shape in which the lines of force do not run parallel but rather converge or diverge in a definite manner. Such an arrangement is desirable e. g. when the deflection is not to be effected with uniform strength over the deflecting space, so as for example to describe a rectangular surface (not a trapezoidal surface) upon an obliquely reposing screen. In such a case, by suitably distributing the windings on the periphery of the cylinder, the desired shape may be given to the deflecting field.

Embodiments are illustrated in the figures of the drawing.

Fig. 1 is a cross section through a deflecting coil and the deflecting space.

Fig. 2 is a schematic side view of the coil of Fig. 1 taken in the direction of arrow A.

Fig. 3 is a cross section through two deflecting coils pushed into each other, each being turned 90°.

Fig. 4 is a cross section through a coil by means of which the field is compressed in one direction.

The coil shown in Figs. 1 and 2 and provided with longitudinal conductors 1 and side conductors 2 produces a homogeneous field 3 in its interior. A dividing surface 4 may be passed through the electrical axis of the coil said surface lying perpendicular to the axis of the cylinder or tube. The portions of the side conductors 2 lying between the pairs of longitudinal conductors are preferably so bent around that they lie outside the cylindrical internal space formed by the longitudinal conductors. As shown in the schematic representation of Fig. 2 the windings which constitute the side conductors 2 are closer together than the windings of the longitudinal conductors 1 and the separations between the windings of the side conductors are uniform.

If the arrangement is such that the side conductors 2 lie within the cylinder exteriorly enshrouding the longitudinal conductors, two of the tubular coils 5 and 6 may be pushed into each other as shown in Fig. 3. The axis of coil 5 may then be displaced 90° with respect to the axis of coil 6. The arrangement in this case is preferably so chosen that the coils may subsequently be displaced with respect to each other at least to a small angular amount. In order to obtain as homogeneous a field as possible, the longitudinal conductors are not distributed in a constant manner on the periphery of the circular cylinder, but in such a manner that the separation of the conductors or con-

ductor groups projected on the axial section is constant for the same total current, as indicated in Fig. 1 by the heavier and lighter crosses and circles. The individual conductors are therefore 5 distributed in varyingly dense manner and in such a manner that the windings of longitudinal conductors 1 which are furthest removed from the axis of the coil, lie closely against each other. The closer the longitudinal windings approach 10 the axis of the coil, the more does the separation between the individual windings of longitudinal conductors 1 increase.

In order to give the magnetic fields produced by coil 2 a shape such as is indicated for example in Fig. 4, an unsymmetrical distribution 15 of the windings is used with respect to the cross section plane 7 in accordance with the crosses and points shown in Fig. 4.

The coil of the invention may also be disposed 20 within the tube, for which purpose it is mounted preferably on a ceramic member provided with recesses and/or grooves for receiving the individual wires or groups of wires. A suitably shaped carrier for holding the coil may also 25 be used exteriorly of the evacuated tube.

In some cases it may be preferable to form the coil as a cone in order to be able to enshroud all of the space occupied by the deflected 30 ray as closely as possible.

30 I claim:

1. In combination with a cathode ray tube, means for producing a ray deflecting field having a controlled intensity distribution in a plane 35 normal to the undeflected ray axis, comprising deflecting coils having a plurality of turns, each turn having a plurality of turns, each turn having side conductors disposed parallel to the undeflected ray axis of said tube and end conductors concentric about said axis, said side conductors defining a cylindrical surface.

40 2. In combination with a cathode ray tube, means for producing a ray deflecting field having a controlled intensity distribution in a plane normal to the undeflected ray axis, comprising 45 deflecting coils having a plurality of turns, each

turn having a plurality of turns, each turn having side conductors parallel to, and end conductors concentric about the undeflected ray axis of said tube, said coils being so bent around the axis of said tube that said side conductors define a cylinder and are evenly spaced around the cylinder thus defined. 5

3. In combination with a cathode ray tube having a conical shape, means for producing a ray deflecting field having a controlled intensity 10 distribution in planes normal to the undeflected ray axis, comprising deflecting coils having a plurality of turns, each turn having a plurality of turns, each turn having side conductors disposed along elements of a core whose axis is the 15 axis of the undeflected ray and end conductors concentric about the undeflected ray axis of said tube, said coils being so formed about the axis of said tube that said side conductors define, and are evenly spaced about, a conical surface 20 coaxial with said tube.

4. In combination with a cathode ray tube, means for producing a ray-deflecting field of uniform strength in a plane normal to the undeflected ray axis, comprising deflecting coils 25 having a plurality of turns, each turn having a plurality of turns, each turn having end conductors concentric about said axis, and side conductors parallel thereto, said end conductors being so bent about said axis that said side conductors define a cylindrical surface, said side conductors being evenly distributed about the surface so defined. 30

5. In combination with a cathode ray tube having opposed deflecting coils formed thereabout 35 with side conductors parallel to, and end conductors concentric about the undeflected ray axis, said side conductors being positioned to define a cylinder concentric about said axis, means for producing a more intense field on 40 one side of said coils and symmetrical about a plane dividing said opposed coils, comprising a concentrated side conductor spacing on the side adjacent the desired intense field.
